UNITED STATES PATENT OFFICE.

SANFORD L. CLUETT, OF TROY, NEW YORK, ASSIGNOR TO CLUETT, PEABODY & CO., INC., OF TROY, NEW YORK, A CORPORATION OF NEW YORK.

FOLDING MACHINE.

Application filed December 8, 1925. Serial No. 74,002.

This invention pertains to pressing and folding machines of that class employed in the commercial production of collars, relating particularly to means for accurately 5 mortise-locking the points and evenly turning the edges to secure smooth and unwrinkled seams.

It is very important in forming a mortise lock that the primary fold be made in exact 10 relation to the main or secondary folds; otherwise imperfect points will result. Heretofore the primary fold has been made directly with the fingers or with a device carried in the fingers of the operator. Obviously with this method accuracy in forming the primary fold is dependent wholly upon the individual skill of the operators and inevitably cannot be precise even though the operators be most skilled.

20 The objects of the present invention are to provide means whereby in forming mortise locks on the ends of collars the primary fold will at all times be made in a predetermined relation to the main folds; to provide 25 a movable claw which automatically moves out of range of the die when released; to provide a movable claw having a heat insulated surface to protect the fingers of the operator; to provide a claw attached to and 30 made a part of the folder plate for accurately folding the collar; and to provide a device which will be simple in construction and efficient in operation.

In order to fold collar blanks accurately 35 I have devised the present improvement for attachment to the folding plates to assure correct turning of the primary fold. This improved means comprises abutments for holding the blank on the bed plate and table 40 in correct position and means on the folding plates for accurately turning the primary fold in the collar preliminary to the actuation of the die and folder plates.

One embodiment for carrying this invention into effect is shown in the accompanying drawings in which,—

Fig. 1 is a plan view of the folding machine with parts omitted;

Fig. 2 is a section on line 2—2 of Fig. 1 50 with the claw in retracted position;

Fig. 3 is a view similar to Fig. 2 with the claw in folding position;

Figs. 4, 5 and 6 are detail plan views of the presser and folder plates illustrating suc-

cessive steps in making the mortise lock after 55 the primary fold has been made;

Fig. 7 is a fragmentary plan view of a collar blank with a primary fold therein; and

Fig. 8 is a fragmentary plan view of the 60 collar blank after the main or secondary folds have been turned.

These pressing and folding machines are in general of well known construction, comprising a frame 0, a heated bed plate 1 65 mounted in a central opening in the frame, a presser arm 2 and folding plates 3 and 4. The two folding plates are practically identical in construction, except that one is adapted to fold the right ends of the collars, 70 and the other is adapted to fold the left ends of the collars. Each folding plate comprises a thin metal sheet 5 contoured on its inner edges to conform with the corresponding edges of the collar blanks and die. This 75 base sheet is secured to the under side of a heavier plate 6 having a raised extension 7 slotted at 8 in order to be adjustably connected with a bar 9 by means of clamping bolts and nuts 10. An eccentric 11 engages 80 with the bar 9 for oscillating each folding plate over the surface of the bed plate in the direction of the arrow. Cleats 12 are secured to the frame 0 overlying the folding bars to maintain the sliding bars in close 85 contact with the bed plate.

The points of the collar blank at the junction of the front and bottom edges are mortise locked, such locking comprising first making a primary fold 13 (Figs. 4 and 7) 90 of the corner upon the main portion of the collar blank and then making the main or secondary folds 14 and 15 along the front and bottom edges of the blank respectively. The illustrations in Figs. 4, 5 and 6 show 95 the successive steps in forming the main or secondary folds after each primary is made. The actuating eccentrics move the folding plates first substantially longitudinally towards each other to form the end folds and then swing inwardly to overlap the edge fold on the end folds. It is very important that the aforesaid primary fold should be made in exact relation to the main or secondary folds, that is through the point of intersection 16 of the folding lines 17 and 18 (Fig. 7) and in order to accomplish this the collar blank is positioned correctly in respect to the

folding plates by means of abutment 19 and gauge 20 against which the bottom and top edges of the blank respectively bear. Both the abutment and gauge are attached to the folding plate, the former being attached in any suitable manner as by rivets 21 and the latter being adjustably connected by means of an elongate slot 22 and clamp screw 23, all as described in copending application of 10 Thomas J. Abbott filed on even date here-with.

In a predetermined position upon each folding plate there is fixed by screw 24 a primary folder comprising a supporting plate 25 and a manually operable claw 26. Each claw is pivotally connected with its supporting plate by means of upstanding lugs 27 on the plate and a pintle 29 journaled in the lugs. One end of the supporting plate is bent downwardly at 30 to contact with the top surface of the folder plate to form therewith an angle somewhat less than 90°. This bent end is recessed at 31 to permit the presser die 32 to move down 20 upon the blank and primary fold and its forward face 28 is roughened or knurled to hold the primary fold in position after disengagement by the claw until pressed down by the presser die 32 (Figs. 4-6). The claw 25 is provided with a creasing blade 33 bent at substantially the same angle as the face 30 of the supporting plate and also with an insulation handle 34. A tension spring 35 has one end suitably attached to the primary 30 folder at 36 and the other end attached by screw 37 to the folder whereby the primary folder when released by the operator will return to normal position and out of range of the die. In the folding plate at the intersecting edges which conform to the contour of the collar there is an extended slot 38 in order that the folder plate will clear the edge of the bottom fold 15 in its initial movement by the eccentric to overturn the end fold 14; then after the end fold has been overturned, the continued circular movement of the plate then causes the bottom 45 fold 15 to be folded over the presser 32. The two plates are overlapped at 39 and connected by means of a tongue and groove connection 40 in order to maintain parallel movement toward and from each other as they are swung over the surface of the bed plate by eccentrics 11.

50 In the operation of the device the collar blank is inserted between the two plates and positioned in respect thereto by the aforementioned abutment 19 and gauge 20 carried by each folding plate. With the blank properly positioned between the plates the primary folders 26 are actuated to make the primary folds 13 and when released are automatically returned to normal position, out of range of the die 32, which is actuated to clamp down upon the blank and retain it

upon the bed plate 1 (Fig. 4) while the folder plates 3 and 4 are actuated to make the main folds 14 and 15. By means of the eccentrics 11 the folder plates are initially moved towards each other, thereby turning 70 the end folds 14 (Fig. 5). After the plates have moved sufficiently to overturn the end folds they swing inwardly (upwardly in Figs. 1 and 6) to overturn the bottom fold and complete the main folds. 75

It is understood that the invention is not limited to the details of construction herein described, but that various changes may be made therein such as may occur to those familiar with the art, without departing 80 from the spirit of the invention.

I claim:

1. A folding machine for making mortise-lock folds having a primary fold at a corner of the article and secondary folds along the edges meeting at the corner, the machine having a bed, a presser movable toward and from the bed, and folder plates movable thereover to form the secondary folds, characterized by an abutment connected to one of the folder plates with a surface facing said corner and arranged to contact with the stock being folded, and a claw movably connected to the folder plate to move in a predetermined path relatively to said abutment, said claw being effective to fold the corner of the article into the angle between the folder plate and said surface preliminary to movement of the folder plates and presser to operative position. 95

2. A folding machine according to claim 1 further characterized by means for pivotally supporting said claw to swing from folding position out of the path of the presser. 105

3. A folding machine according to claim 1 further characterized in that said abutment surface and folder plate make an acute angle with each other and the claw is constructed and mounted to swing its folding edge substantially to the apex of said angle. 110

4. A folding machine according to claim 1 further characterized in that said surface is roughened to hold the primary fold in position by friction after the claw is retracted. 115

5. A folding machine for making mortise-lock folds having a primary fold at a corner of the article and secondary folds along the edges meeting at the corner, the machine having a bed, a presser movable toward and from the bed, and folder plates movable thereover to form the secondary folds, characterized by an abutment connected to one of the folder plates with a surface facing said corner and a claw movably connected to the plate to move in a predetermined path relatively to said abutment, thereby to fold the corner of the article into the angle between the folder plate and said surface pre- 125

liminary to folding movement of the folder plates, and a resilient means for returning said claw to normal position.

6. A folding machine for making mortise-lock folds having a primary fold at a corner of the article and secondary folds along the edges meeting at the corner, the machine having a bed, a presser movable toward and from the bed, and folder plates movable thereover, characterized by an abutment connected to one of the folder plates with a surface face making an acute angle with said folder plate the apex of which is at the point of intersection of the secondary folds, and 10 a claw adapted to swing to the apex of said angle.

7. A folding machine for making mortise-lock folds having a primary fold at a corner of the article and secondary folds along the edges meeting at the corner, the machine 20 having a bed, a presser movable toward and from the bed, and folder plates movable thereover characterized by an abutment connected to one of the folder plates with a surface face engaging with the folder plate, 25 and a movable member adapted to swing to the point where the surface face and folder plate meet.

Signed by me at Troy, New York, this twenty-fifth day of November 1925.

SANFORD L. CLUETT.
